CLAIM

I claim the ornamental design for eyeglasses, as shown and described.

DESCRIPTION

FIG. 1 is a perspective view of eyeglasses showing my new design;

FIG. 2 is a front elevation view thereof;

FIG. 3 is a rear elevation view thereof;

FIG. 4 is a right side elevation view thereof, the left side being a mirror image thereof;

FIG. 5 is a left side elevation cross-section view thereof taken along line 5-5 in FIG. 2;

FIG. 6 is a top plan view thereof;

FIG. 7 is a bottom plan view thereof;

FIG. 8 is a front elevation view of an enlarged portion thereof identified as 8-8 in FIG. 2;

FIG. 9 is a rear elevation view of an enlarged portion thereof identified as 9-9 in FIG. 3;

FIG. 10 is a right side elevation view of an enlarged portion thereof identified as 10-10 in FIG. 4;

FIG. 11 is a left side elevation cross-section view of an enlarged portion thereof identified as 11-11 in FIG. 5;

FIG. 12 is a top plan view of an enlarged portion thereof identified as 12-12 in FIG. 6;

FIG. 13 is a bottom plan view of an enlarged portion thereof identified as 13-13 in FIG. 7; and,

FIG. 14 is a top plan view of an enlarged portion thereof, shown in a partially open, partially closed position of use. The broken lines illustrate portions of the eyeglasses that form no part of the claimed design.
